CLAIM

I claim the ornamental design for the ID commuter front pocket wallet, as shown and described.

DESCRIPTION

FIG. 1 is a back view of the ID commuter front pocket wallet showing my new design;

FIG. 2 is a front view thereof;

FIG. 3 is a top view thereof;

FIG. 4 is a bottom view thereof;

FIG. 5 is a left side view thereof;

FIG. 6 is a right side view thereof;

FIG. 7 is an open back view thereof;

FIG. 8 is an open front view thereof;

FIG. 9 is a back perspective view thereof; and,

FIG. 10 is a back perspective view thereof.

The broken line showing of a card in FIGS. 2 and 7 and paper money in FIGS. 9 and 10 is for illustrative purposes only and forms no part of the claimed design.
